CLAIM

We claim the ornamental design for a room with retail arrangement, as shown and described.

DESCRIPTION

FIG. 1 is a front perspective view of a room with retail arrangement;

FIG. 2 is a rear view of the room with retail arrangement, shown inside the walls of the room for ease of disclosure;

FIG. 3 is a front view thereof;

FIG. 4 is a right side view thereof;

FIG. 5 is a left side view thereof; and,

FIG. 6 is a top view of the room with retail arrangement. The broken lines depict portions of the room with retail arrangement that form no part of the claimed design.
